United States Patent Office

Des. 210,631

Patented Mar. 26, 1968

210,631

TYPEWRITER

Carl L. Otto, New York, N.Y., assignor to Litton Business Systems, Inc., a corporation of New York

Filed Jan. 17, 1967, Ser. No. 5,459

Term of patent 14 years

(Cl. D64—11)

Fig. 1

Fig. 2

Fig. 3

FIG. 1 is a perspective view illustrating the front and right side of the typewriter embodying my new design;

FIG. 2 is a left side elevational view of the typewriter shown in FIG. 1; and

FIG. 3 is a rear elevational view of the typewriter shown in FIG. 2.

I claim:

The ornamental design for a typewriter, substantially as shown.
